UNITED STATES PATENT OFFICE

EDWIN O. KLEMM AND KARL R. OTTO, OF SAGINAW, MICHIGAN

DESIGN FOR A COMBINED STUDENT'S CHAIR AND LAMP

Application filed November 22, 1930. Serial No. 37,768. Term of patent 14 years.

To all whom it may concern:

Be it known that we, EDWIN O. KLEMM, and KARL R. OTTO, citizens of the United States, residing at Saginaw, in the county of Saginaw and State of Michigan, have invented a new, original, and ornamental Design for Combined Student's Chair and Lamp, of which the following is a specification, reference being had to the accompanying drawing, forming a part thereof, in which the figure is a perspective view of a combined student's chair and lamp showing our new design.

We claim:—

The ornamental design for a combined student's chair and lamp, substantially as shown.

EDWIN O. KLEMM.
KARL R. OTTO.
